Letters Patent No. 2388. Dated Aug. 14, 1866.

Design for a Fence

The schedule referred to in these Letters Patent and making part of the same

to all whom it may concern:

I, John C. Gearhardt, of Jersey Shore, in the County of Clinton and State of Pennsylvania, have invented a new and improved Design for an Iron Fence, and I do hereby declare that the following is a full, clear and exact description thereof, which will enable others skilled in the art to make and use the same, referring being had to the accompanying drawings forming part of this specification.

My invention relates to a Design for an iron fence, the same consisting of trunks of trees having short trimmed boughs, extending from each side which meet, cross and entwine with each other and have and share a leaf, or branch of leaves, the whole design producing a neat and rustic fence.

The drawing is a photographic representation of a section of a fence, it to designate the bodies of the trees and a, b, c, branched extending from the sides, that is, to the right and left of the trunks, they are short, trimmed and arranged along the trunks to resemble nature as near as possible, and they are arranged so as to meet, cross, and entwine with each other.

b, are leaves, or branches of leaves which are pendent from the boughs, such manner as to fill up open spaces here and there occurring and also so arranged as to add to the rustic appearance of the fence.

What I claim as new and desire to secure by Letters Patent is, the Design for an iron fence, herein shown and described.

The above specification of my invention signed by me this 22nd day of June 1866.

Witnessed, (B. J. Pierce.)
(J. C. Gearhardt.)

J. C. Gearhardt,
